DESIGN FOR A DRESS

Ruth Riff Saifer, St. Louis, Mo.

Application July 24, 1937, Serial No. 70,607

Term of patent 14 years

To all whom it may concern:

Be it known that I, Ruth Riff Saifer, a citizen of the United States, residing at St. Louis, Missouri, have invented a new, original, and ornamental Design for a Dress, of which the following is a specification, reference being had to the accompanying drawing, forming part thereof.

I claim:

The ornamental design for a dress, substantially as shown.

RUTH RIFF SAIFER.
